UNITED STATES PATENT OFFICE.

JOSEPH A. MASONICK, OF LAKE FOREST, ILLINOIS, ASSIGNOR TO J. A. MASONICK COMPANY, OF LAKE FOREST, ILLINOIS, A CORPORATION OF ILLINOIS.

DISH-WASHING MACHINE.

1,293,848.

Specification of Letters Patent. Patented Feb. 11, 1919.

Application filed April 25, 1917. Serial No. 164,431.

To all whom it may concern:

Be it known that I, JOSEPH A. MASONICK, a citizen of the United States, residing at Lake Forest, in the county of Lake and State 5 of Illinois, have invented certain new and useful Improvements in Dish-Washing Machines, of which the following is a specification.

This invention relates to improvements in 10 dish washing machines and one object is to provide a machine of few parts, cheap to manufacture and efficient in operation. With the foregoing and other objects in view the invention consists in the combination and 15 arrangement of parts to be hereinafter fully described, pointed out in the appended claim and illustrated in the accompanying drawings which form a part of this specification and in which—

20 Figure 1 is a side elevation of my improved machine.

Fig. 2 is a top plan view of the same.

Fig. 3 is a vertical sectional view through the machine.

25 Fig. 4 is an enlarged detail sectional view of one of the spraying nozzles.

Like reference characters denote corresponding parts throughout the several views.

The reference numeral 1 denotes a water 30 supply tank adapted to be heated by a gas burner 2^a having gas supply pipe 2 and from said water tank 1 a service pipe 3 leads to the gear pump 4 which is connected by service pipes 5, 6 with the pipe coupling 7 35 which also receives the vertical supply pipe 8 which is arranged centrally of the tub 17 and extends through the packing nut 8^a and bearing 8^b carried by the floor of the tub and through said tub floor. Upper and

40 lower branch pipes 9 provided with suitable spray nozzles 10 are connected by T-coupling to the said supply pipe and extend radially from the said pipe almost to the inner periphery of said tub 17. Each branch pipe 45 9 is formed with perforations 9^a which perforations are encompassed by the said spray nozzles the extensions 10^a of which are formed with perforations 10^b to admit the

screws 10^c, the threaded ends of which are adapted to seat in threaded sockets formed 50 in said extensions 10^a, said screws being formed with the heads 10^d.

Enmeshing gears 12, 13, 14 carried respectively by the said gear pump 4, transmission shaft 15 and stub shaft 14^a may be driven 55 by the handle 14^b of gear 14 to operate the said pump 4. Stub shaft 14^a being journaled in the tub 17 and shaft 15 in bearings 15^a, 15^b, said shaft 15 being driven also by said gears and said shaft 15, further, being 60 provided terminally with a bevel gear 16 in mesh with a terminal bevel gear 17^a of supply pipe 8 whereby said supply pipe is rotated to cause rotation of said branch pipes 9 in horizontal planes within the said tub 65 17. The tub 17 is provided with an outer peripheral band 18 to which the supporting legs 19 are secured. Within the said tub 17 the dish-carrying baskets 20 are arranged upon a supporting screen 21, the ends of 70 which are secured to the tub wall. The said baskets and screen 21 are placed between the horizontal planes of rotation of the said branch pipes 9 and the water directed from the nozzles of said pipes, in opposite directions, enters said baskets from the top and bottom and washes and thoroughly rinses the dishes. A suitable drain pipe or faucet (not shown) is provided for the said tub 17.

What is claimed is:—

In a dish washing machine, the combination with a tub, of a vertical rotatable water feed pipe centrally positioned in the tub, a coupling in which the upper end of the pipe is journaled and having communication with 85 the interior of the pipe, mechanism connected to the lower end of the pipe to rotate it, and a source of water supply connected to the coupling.

In testimony that I claim the foregoing 90 as my own I have hereto affixed my signature in the presence of two subscribing witnesses.

JOSEPH A. MASONICK.
